US00D788266S

(12) **United States Design Patent** (10) **Patent No.:** **US D788,266 S**
Ito et al. (45) **Date of Patent:** **** May 30, 2017**

(54) **EJECTOR VALVE**

(71) Applicants: **SATAKE CORPORATION**, Tokyo (JP); **MECHANO TRANSFORMER CORPORATION**, Tokyo (JP); **KURODA PNEUMATICS LTD.**, Asahi-shi, Chiba (JP)

(72) Inventors: **Takafumi Ito**, Hiroshima (JP); **Sze Keat Chee**, Tokyo (JP); **Toshitada Hirata**, Asahi (JP); **Toshiro Higuchi**, Tokyo (JP)

(73) Assignees: **Satake Corporation** (JP); **Mechano Transformer Corporation** (JP); **Kuroda Pneumatics Ltd.** (JP)

(**) Term: **14 Years**

(21) Appl. No.: **29/516,673**

(22) Filed: **Feb. 5, 2015**

(30) **Foreign Application Priority Data**

Aug. 7, 2014 (JP) 2014-17260

(51) **LOC (10) Cl.** **23-01**

(57) **CLAIM**

We claim the ornamental design for an ejector valve, as shown and described.

DESCRIPTION

FIG. 1 is a perspective view of an ejector valve showing our new design, as seen from above and to the right;

FIG. 2 is a perspective view of an ejector valve showing our new design, as seen from below and to the right;

FIG. 3 is a front elevational view thereof;

FIG. 4 is a rear elevational view thereof;

FIG. 5 is a left side view thereof;

FIG. 6 is a right side view thereof;

FIG. 7 top plan view thereof; and,

FIG. 8 is a bottom plan view thereof.

1 Claim, 8 Drawing Sheets
